UNITED STATES PATENT OFFICE.

HECTOR V. LOUGH, OF PLAINFIELD, AND WALTER E. LOUGH, OF NORTH PLAINFIELD,
NEW JERSEY.

BEDSTEAD CORNER-BRACKET.

1,082,754.

Specification of Letters Patent. Patented Dec. 30, 1913.

Application filed December 10, 1912. Serial No. 735,907.

To all whom it may concern:

Be it known that we, HECTOR V. LOUGH and WALTER E. LOUGH, subjects of the King of Great Britain, residing at Plainfield, county of Union, and North Plainfield, county of Somerset, State of New Jersey, respectively, have invented certain new and useful Improvements in Bedstead Corner-Brackets, of which the following is a full, clear, and exact description.

This invention relates to corner brackets for bedsteads, by which the side rails are detachably connected to the head and foot-board, and its chief object is to provide an improved sheet metal bracket of simple construction, which can be manufactured at low cost and which shall possess the necessary strength and rigidity.

To this and other ends the invention consists in the novel features of constructions and combinations of elements hereinafter described, and more particularly set forth in the appended claims.

One form of the invention is illustrated in the accompanying drawings, in which—

Figure 1 is a side view, partly in vertical section, showing my improved corner bracket applied to a metal bedstead. Fig. 2 is a plan view of the same, partly in horizontal section and with a small portion broken away. Fig. 3 is a perspective view of the two parts of the bracket, separated or disengaged from each other. Figs. 4 and 5 are plan views of the sheet metal blanks from which the two parts of the bracket are made.

The bracket-part or member 10, which is attached to the foot or head-board comprises a tubular body portion having a top 11, and an outer side wall 12 and an inner side wall 13, and a bottom 14. The top and bottom are provided with lugs or extensions 15, 16, formed with transversed heads 17, 18, having notches 19, 20, in their inner edges, in line with shoulders 21, 22, on said lugs or extensions. In attaching the bracket-part 10 to a foot or head-board the extensions 15, 16, are inserted into horizontal slots 23, 24, in the tubular post 25, which slots are wide enough to admit the shoulders 21, 22, as clearly shown in Fig. 2. A key or wedge 26, in the form of an inverted U with tapering legs, is then driven down into the notches 19, 20, embracing the shoulders 21, 22, and by engagement with the inner surface of the

post drawing the end edges of the side walls, 12, 13, firmly against the outside of the post. The bracket-part or member is thus securely attached to the post but can be removed by merely withdrawing the key or wedge 26. To divide the stress, exerted by the key, equally between the two extensions or lugs 15, 16, the latter is made shorter than the other, as shown in Figs. 1 and 2. This makes the open slots or notches 19 farther from the inner surface of the side of the post 25 next to the bracket body 10, than are the notches 20. Then when the tapered key 26 is driven down into place, as in Fig. 1, both extensions 15 and 16 aid in drawing the body 10 up against the outside of the post; whereas if the extensions 15, 16, were of equal length, and the notches 19, 20, therefore at equal distances from the aforesaid inner surface of the post the inclined edges of key 26 would not come in contact with the bases of the lower notches 20 and hence all the work of holding the body 10 against the post would devolve upon the upper extension 15.

The means described, for connecting the bracket member 10 to the post, constitutes an important feature of the invention, being universal in application; that is, it enables the bracket member to be attached to posts of different sizes, and to square as well as to round posts. At the other end, the top 11 and the bottom are provided with extensions 27, 28, connected by an end wall 29 having inwardly turned inclined edges 30, 31; that is, the inturned edges are wider at the bottom than at the top, to form inclined ribs or rails for coöperation with corresponding edges or beads on the member which is attached to the side rail. Extending laterally from the side wall 13 is a tongue 32 for attachment to the head or foot rail (not shown) extending between the head or foot posts. The bracket-part or member 33 is also of tubular form, composed of a top 34, inner and outer side walls 35, 36, and a bottom 37. The side walls are extended past the top and bottom and have their edges turned back in a vertical plane to form inner inclined edges 38, 39, said inturned edge-portions being wider at the top than at the bottom to coöperate with the oppositely inclined edge-portions 30, 31, on the bracket member 10. On the top and bottom 34, 37, respectively, are lugs or extensions 40, 41,

which are bent inwardly or toward each other into a vertical plane to form, in effect, an end wall in rear of the edges or shoulders 38, 39.

5 The bracket member 33 is attached to the angle-iron side rail 42 of the bedstead by means of rivets 43, the parts arranged as shown, with the flange of the side rail on top of the bracket member.

10 In assembling the bedstead the bracket member 33, attached to the side rail, is brought over the member 10 and dropped down into position, the inclined edges 30—31 and 38—39 coöperating to crowd the two end walls 29 and 40—41 tightly together. The bracket parts are thus not only held firmly against lateral displacement but also against pivotal movement of either relative to the other. In fact the two parts when joined 15 are practically as rigid as a single piece. At the same time they can be readily disconnected whenever desired. By preference the extension 27 on the top of the part 10 is offset downwardly, as shown in Fig. 1, to permit the top of the side rail 42 to lie flush with the top of the part 10.

The parts are so designed that they can each be made of a single piece of sheet metal stamped or otherwise cut to the proper 20 shape and then bent, to form the bracket part. The blank from which the part 10 is made is illustrated in Fig. 4, and has the general shape of a cross having a lower or long arm 44, an upper or short arm 45, and lateral or cross-arms 46, 47. Near the lateral arms the lower or long arm is formed with a trapezoidal portion 48 the shorter of whose parallel sides is nearest the said lateral arms. Extending toward said trapezoidal portion 25 35 the arm 47 has a tongue 32^a provided with rivet holes 49. In forming the bracket part 10 the blank is given 90° or right-angle bends upwardly along the dotted lines 50, 51, 52, 53, 54, 55, 56, 57, and downwardly along 40 the line 58, at the same time offsetting the neck 27^a. This brings the blank exactly to the form shown at 10 in Fig. 3, with the ends of the arms 46, 47, dovetailing in the correspondingly shaped sides 59 of the long 45 arm 44, after which the dovetails are hammered to spread their edges into a tight and immovable fit. It will, therefore, be seen 50 that the bracket member 10 is made of a single piece of sheet metal without rivets, 55 all the projecting "operative" parts, so to speak, being integral with the body of the device. It will be obvious in Fig. 2 that the legs of the key 26 engage not only the shoulders at the juncture of the extensions 60 15, 16, with the top and bottom walls of the bracket member, but also the adjacent inner surface of the post 25. This is a desirable feature, as it aids in holding the dovetails together, as will be readily understood.

65 The part 33 is also made of a single sheet

metal piece or blank, having, roughly, the shape of the letter E, as shown in Fig. 5. The arms 60, 61, 62, extending from one side of the body portion 63, have their edges inclined as shown, and between the arms are two lugs 40^a, 41^a. At its ends the body 63 is formed with a notch 64 and a corresponding lug 65, and with rivet holes 43^a adjacent thereto. In forming the bracket-part 33 the blank described is bent upwardly 90° along the dotted lines 69, 70, 71, 72, 180° along 66, 67, 68. This brings the blank to the exact form shown at 33 in Fig. 3, with the lug 65 fitting in the notch 64. The member is then applied to the side rail and is riveted thereto by means of the rivets 43 extending through the holes 43^a in the side wall 36 and through registering holes in the side of the rail 42. The rivets mentioned thus serve not only to fasten the bracket member to the side rail but also to hold the contacting edges of the bracket member together.

From the foregoing it will be seen that my invention provides a simple device which can be manufactured at low cost and which when made of suitable material possesses ample strength and rigidity. It will be observed that the design of the parts is such that the heaviest stresses to which the parts are subjected are exerted as tension or compression. Thus, for example, the stress on the top 11 is a pull, tending to draw the head 17 out of the bed post but resisted by the key 26. The stress on the bottom 16 is a push, tending to push the head 18 away from the key 26 but resisted by the dovetails in said bottom, the said walls 12, 13, being held rigidly in position by the bed post, against which said side walls bear.

It is to be understood that the invention 105 is not limited to the structure herein specifically illustrated and described, but can be embodied in other forms without departure from its proper spirit and scope, as defined by the following claims:

We claim:

1. In a corner bracket for bedsteads, in combination, a bracket member comprising a tubular body having at an end extensions connected by an end wall, having inclined edge-portions which are bent back toward the body; and a bracket member comprising a tubular body having side walls with inclined edge-portions bent inwardly to cooperate with the inclined edge-portions of 115 the first named member.

2. In a corner bracket for bedsteads, a tubular member having top, bottom, and side walls; endwise extensions from the top and bottom walls; an end wall connecting said extensions and having inclined edge portions extending rearwardly toward the body; in combination with a second tubular member aligned with the first, having side walls provided with inclined end-edges ex- 125 130

tending inwardly to coöperate with the inclined edge-portions of the first member; and means for attaching one of said members to a bedpost, the other being adapted for attachment to a side-rail of the bedstead.

5 3. In a corner bracket for bedsteads, a tubular bracket member having top and bottom walls having at one end means for attachment to a bedpost, and at the other end having endwise extensions connected by an end wall formed with inclined rearwardly turned edge-portions, said bracket member having a side wall provided with means for attachment to an end rail of the bedstead.

10 4. In a corner bracket for bedsteads, a tubular sheet-metal member comprising horizontal top and bottom walls, and side walls integral therewith; upper and lower extensions at one end, integral with said top and bottom walls; a vertical end wall connecting said extensions and integral therewith; inclined rails integral with the end wall at the sides thereof and extending toward the said side walls; and a tongue integral with one of the side walls and extending laterally therefrom.

15 5. In a corner bracket for bedsteads, a tubular sheet-metal member comprising horizontal top and bottom walls, and side walls integral therewith; means at one end of the member for connection with the side rail of a bedstead; and horizontal endwise extensions at the other end, integral with the top and bottom walls and provided with transverse heads adapted to extend into

horizontal slots in a hollow bedpost and 40 formed to receive a wedge-key between them and the inner surface of the post.

6. In a corner bracket for bedsteads, a tubular sheet-metal member having top, bottom, and side walls; means at one end for 45 connection with the side rail of the bedstead; and horizontal endwise extensions at the other end provided with transverse heads, said extensions having lateral shoulders at their juncture with the top and bottom walls; in combination with a tubular bed-post having horizontal slots to receive 50 said extensions and shoulders; and a U-shaped key movably positioned between the transverse heads and the inner surface of 55 the post, straddling the said extensions and lateral shoulders.

7. In a corner bracket for bedsteads, a tubular member having top, bottom, and side walls, the side walls being extended 60 beyond the top and bottom walls at one end and having inclined edge-portions bent toward the body of the member, and the top and bottom walls having extensions bent respectively downward and upward. 65
